UNITED STATES PATENT OFFICE.

LEON MEUNIER, OF CLEVELAND, OHIO, ASSIGNOR TO CHICAGO PNEUMATIC TOOL COMPANY, OF NEW YORK, N. Y., A CORPORATION OF NEW JERSEY.

PLUNGER-SWITCH MECHANISM.

Application filed July 17, 1925. Serial No. 44,198.

This invention relates to electrical control devices or switches and is of general application although designed and intended for use on hand tools, it particularly concerns 5 switches utilizing a rotary block engaged by spring contacts and has special reference to the structure of the plunger device which effects rotation of the switch block.

In switches of the type described the push 10 member or plunger carries a pivoted pawl which engages shoulders or teeth on the switch block to rotate the latter. The shoulder or tooth on the block rocks the pawl on its pivot against the tension of a spring as 15 the block is turned to its new position and as the plunger is retracted. The spring for restoring the pawl to operative position, as heretofore used, has been of round or flat 20 spring material with a single straight or slightly bent section which had to resist the movements of the pawl. The frequent flexing of this section of the spring produced by the stopping and starting of a portable tool soon results in fatigue of the metal of 25 the spring and breakage, whereupon the manual control device for the switch becomes inoperative.

Among the objects of the invention are to 30 prevent failure of switches of the type described, to provide a switch structure in which breakage strains on the springs is largely if not entirely eliminated, and in general to improve prior devices of the class described in the interests of more efficient 35 and satisfactory service.

In order to illustrate the invention one 40 concrete embodiment thereof is shown in the accompanying drawings, in which:

Fig. 1 is a side elevational view showing 45 the tool casing broken away.

Fig. 2 is fragmentary vertical sectional view substantially on the line 2-2 of Fig. 3 but showing the plunger depressed.

Fig. 3 is a transverse sectional view substantially on the line 3-3 of Fig. 1.

The invention is illustrated as embodied 50 in the manual control handle A for a portable electric tool of which a portion of the casing B thereof is indicated in Fig. 1. The 55 control switch mechanism is mounted in the grip portion A' of Handle A which is hollow for this purpose and has a removable cover plate a secured in place by screws a'. The switch mechanism comprises the block 4, mounted for rotation on a pivot 4^a sup-

ported in the handle, having diametrically opposed plane surfaces engaged by spring contacts 5 supported on a fixed insulated block 6 which may have an insulating division plate 7. Rotatable block 4 has two of 60 its opposed faces 4^b of conducting material which may be interconnected by suitable means such as transversely disposed plates 4^c. The leads to and from the spring contacts 5 may pass through a bore in the lower 65 portion of the handle A, the power for operating the tool being received through a cable D.

Suitable means are provided for stepping block 4 around in order to operate tool B at 70 will. The means on block 4 for this purpose may comprise a centrally disposed ratchet wheel 4^d presenting teeth or shoulders 4^e forming sockets to be engaged in accordance with the usual practice by a pawl member 8. 75 The improved means by which this pawl member 8 is retracted to operative position after being displaced by one of the ratchet teeth 4^e and constituting the present invention will now be described. Pawl 8 is pivoted 80 at 9 in the bifurcated forward end of a manually operable plunger 10 mounted for sliding movement in a differential bore a² in the upper end of grip A'. A coiled spring 11 seated in the forward end of the large 85 bore and engaging a shoulder on plunger 10 normally urges the latter to the position shown in Figs. 1 and 3. Plunger 10 has a central bore 12 terminating adjacent its bifurcated end within which is slidably 90 mounted a cup shaped abutment member 13 backed by a coiled spring 14 retained in plunger 10 by a screw plug 15 closing the outer end of bore 12. Abutment member 13 has a plane face engaging a straight edge 8' on 95 pawl 8 normally disposed transverse to the axis of plunger 10, so that in the retracted position of plunger 10 (Fig. 1) pawl 8 is disposed substantially in line with plunger 10 to engage one of the teeth 4^e of ratchet 100 wheel 4^d.

The operation of the switch mechanism will be apparent from Figs. 1 and 2. With the parts in the position shown in Fig. 1 pressure on the plunger 10 by the thumb of 105 the operator forces the plunger inwardly against the pressure of spring 11. Pawl 8 as it advances forces block 4 to rotate in a counterclockwise direction. As block 4 in its rotation snaps into its next position the 110

following tooth 4^e engages pawl 8 and rocks it on its pivot 9 to the position indicated in Fig. 2 wherein abutment 13 is displaced rearwardly against its coiled spring 14. As the operator releases plunger 10, spring 11 restores it to its former position (Fig. 1) and pawl 8 is drawn rearwardly of the tooth 4^e and on clearing the same, the spring pressed abutment 13 restores pawl 8 in an obvious manner again to operative position as shown in Fig. 1.

From the above it will be apparent that the improved switch mechanism herein disclosed largely eliminates, if not entirely avoids, the chance of failure in switch mechanism of the type described through breakage of springs in the manual control structure, by reason of the use of coiled springs which are not subjected to acute flexes and strains, and it is to be understood that the invention is not confined to the specific details herein disclosed but covers all changes, adaptations and modifications within the scope of the appended claims.

25 I claim as my invention:

1. In an electrical control device having a rotatable switch block provided with circumferentially spaced sockets, a plunger for rotating said block having a pivoted pawl for engagement in said sockets, and means movable axially within said plunger for maintaining said pawl in operative position but permitting rocking movement on its pivot in response to rotation of said block effected by said plunger.

2. In an electrical control device having a rotatable switch block provided with circumferentially spaced sockets, a plunger for rotating said block having a pivoted pawl for engagement in said sockets, said plunger having a bore rearwardly of said pawl, and a yielding abutment member for said pawl slidable within said bore arranged to be forced rearwardly as the plunger is advanced 45 to rotate said block, said rearward movement of said abutment permitting rocking movement of said pawl.

3. In an electric switch having a rotatable switch block provided with circumferentially spaced sockets, manual control means therefor comprising a spring pressed plunger, a pawl pivoted adjacent the forward extremity of said plunger and presenting a rearward face transverse to the axis of said plunger, a spring pressed abutment movable axially within said plunger and presenting a flat face for engagement with the transverse face of said pawl, said abutment being forced rearwardly by the

rocking of said pawl upon its pivot as the plunger is advanced to cause the pawl to rotate said block.

4. In an electric switch having a rotatable switch block provided with circumferentially spaced sockets, manual control means therefor comprising a spring pressed plunger, a pawl pivoted adjacent the forward extremity of said plunger and presenting a rearward face transverse to the axis of said plunger, said plunger having a bore rearwardly of said pawl, an abutment slideable in said bore and presenting a flat face to engage said transverse face of said pawl, and a compression spring in said bore engaging said abutment, said abutment being forced rearwardly by the rocking movement of said pawl upon its pivot as the plunger is advanced to cause the pawl to rotate said block.

5. In an electric switch having a rotatable switch block provided with circumferentially spaced sockets, manual control means therefor comprising a spring pressed plunger, a pawl pivoted adjacent the forward extremity of said plunger and presenting a rearward face transverse to the axis of said plunger, said plunger having a longitudinal bore therein, terminating rearwardly of said pivot, a cup shaped member slideable in said bore and presenting a face for engagement with said face of said pawl, a plug closing the rearward end of said bore, and a coiled spring interposed between said plug and said member and extending within the latter for maintaining said member and said pawl in engagement.

6. In a handle attachment for portable electrical tools having a grip portion, a switch within said portion comprising a rotatable block and yielding contacts engaging opposite faces thereof, manual means for stepping said block around comprising a spring pressed plunger projecting from a bore in the upper part of said grip portion, a pawl pivoted on the outer end of said plunger for engagement with ratchet teeth on said block, an abutment member slidably mounted in a bore in said plunger to engage said pawl rearwardly of its pivot, and a coiled spring engaging said member within said bore, said member being forced rearwardly in said bore by the rocking movement of said pawl on its pivot as the plunger is advanced to produce rotation of said block by said pawl.

Signed by me at Cleveland this 8th day of July 1925.

LEON MEUNIER.
